LAMP SEALING APPARATUS

Roland M. Gardner, Swampscott, and Ralph L. Allen, Beverly, Mass., assignors to Hygrade Sylvania Corporation, Salem, Mass., a corporation of Massachusetts

Application June 28, 1940, Serial No. 342,963

8 Claims. (Cl. 176—2)

This invention relates to the sealing of vitreous vessels and, more particularly, to tipping off exhaust tubes of electric gaseous discharge lamps.

The primary object of my invention is the tipping off of the exhaust tubing of lamps when the lamps are in an inverted position in the exhaust rubber in comparison to the usual position of incandescent lamps on an exhausting machine i. e., the exhaust heads are positioned at the upper extremity of the machine, having the lamps suspended therefrom. The invention may, for example, be used in an exhaust machine of the turret type shown in U. S. Patent 1,210,620, issued January 2, 1917, to J. T. Fagan et al.

A further object is the provision of a method of tipping off exhaust tubing wherein the seal obtained thereby is a properly annealed one.

Still another object of my invention is the provision of a means by which the lamp may be moved in a downward direction, so as to effect the tipping operation after sufficient heat has been applied to the tubing to cause it to start to melt.

Further objects and features of my invention will be apparent from the following specifications taken in conjunction with the accompanying drawings in which:

Figure 1 is a side elevational view of the tipping torch according to my invention;

Figure 2 is a top view of the scissors-like lower baffle plate with the burners and burner-shield in place;

Figure 3 is a side view in section of the lower baffle plate showing the burner shield and burner parts.

Figure 4 is a top assembly view of the slide on which the torch is mounted;

Figure 5 is a perspective view of the saddle in which the torch proper is mounted.

Figure 6 is a rear sectional view of the tipping torch and the lamp in the heating position.

Figure 7 is a side elevational view of the tipping torch cams and the supporting frame.

Figure 8 is a front elevational view partly in section of the cams and the frame.

Similar reference characters refer to similar parts throughout the several views of the drawings and in the specifications which follow:

In the manufacturing of electric gaseous discharge lamps, the problem of providing an adequate tipping-off torch has proved a troublesome one. Since experience has proven the advisability of exhausting these lamps in an inverted position in comparison to the exhausting position of incandescent lamps, the tipping-off

methods used in the incandescent lamp industry could not readily be adopted in the exhausting of electric gaseous discharge lamps.

The exhausting process in the manufacturing of electric gaseous discharge lamps is performed through an exhaust tube located in, and projecting from the center of the stem which is sealed to the bulb neck. The lamps are set into the exhausting machine by projecting the exhaust tubing of each lamp up into a port or head which, as it indexes around the machine, will successively establish the lamp in connection with a vacuum pump, a line of an inert gas and such other contacts as are desired. The lamp is held in its proper position, suspended from the port, by a jaw chuck which grips the lamp at about its mid-point, thus relieving much of the tension placed on the exhaust rubber of the port or head. The bulb, having gone through the various processes necessary for properly exhausting an electric gaseous discharge lamp, is then ready to be tipped off.

When the lamp, 1, reaches a position directly behind the tipping torch, the torch moves in towards the exhaust tubing, 2, of the lamp. The baffle plate 3 of the torch pivots about the stud 5 as a center, to which it is connected by metal plate 13 and saddle 28, as hereinafter described, in such a manner as to compensate for any slight variance in the vertical alignment of the tubing 2, in the line of motion of the torch. This motion is limited by the stud 55 in the elongated slot 56. This compensating arrangement is made necessary by reason of slight variances that might be present in the flares of the lamp and/or the exhaust tubing. Even a slight variance in these parts would throw the torch and exhaust tubing out of alignment. A channel, 6, narrowing down to the width of an exhaust tube at its end, runs part way down the middle of the top baffle plate, 3, from its forward extremity, thus serving as a guide in centering the torch in its proper alignment with the tubing. The lower baffle plate, 4, is a scissors-like member of two parts 4, 4, meeting and forming a channel, 7, at its forward end, similar to the one in the top plate.

When this alignment variance has been corrected, the torch is ready to move in and encircle the tubing in the hole 8 at the apex of the tipping cone formed by the burner shields 18 and 19. This is accomplished by the action of the scissors-like lower baffle plate, 4. A small spring 55 is sensitive to the slightest tension is located at

a point directly behind the tipping cone, 8, and is joined to the shears of the scissors-like baffle plate. When the torch reaches that point in its forward projection where the exhaust tubing makes a contact with the outer section of the tipping cone adjacent to the channel 7, the slight force exerted thereby will cause the shears of the baffle plate 4 to pivot on the studs 57 and 58 thus opening the shears of the baffle plate 4 and allowing the tubing to enter the tipping cone. When the torch has been projected forward sufficiently to allow the tubing to enter the hole 8 in the tipping cone, the tension on the spring 9 created by the opening of the shears of the baffle plate will cause the jaws of the lower baffle plate 4 to resume their closed position, thus completely encircling the tubing in the tipping cone formed by the burner shields, 18 and 19.

Since the distance of the normal forward motion of the torch moving in, encircling the exhaust tubing until the tubing is in the tipping cone, is a predetermined one, provision must be made for irregularities in the vertical alignment of the torch and the tubing in the line of motion of the torch. If the tubing is not exactly perpendicular and exactly centered in the stem, the torch will either project itself in too far or not far enough in order to center the tubing in the tipping cone. To provide for this, the saddle 28 with the pin 29 held in elongated slots 30 and 31 by the cotter pins 32 and 33 is employed. Thus, when the torch moves in to center the tubing in its tipping cone, an allowance equal to the length of the elongated slots is available to properly center such exhaust tubings as are not in exact perpendicular alignment. Thus the torch may move forward or backward on the pin 29 providing the variance equal to the length of the elongated slots 30 and 31.

An oxygen gas line 14 and a low pressure air line 15 lead in to two small burners 16 and 17 which are located opposite each other and flush on the top of the shears of the scissors-like baffle plate 4 directly over the tipping chamber 8. Burner shield sections 18 and 19 are joined to the lower surface of the lower baffle plate 4 and are conical in shape.

Once the torch has located itself so that the exhaust tubing extends down through the tipping cone the whole torch drops down on to the top of the lamp in such a manner that the conical shaped burner shield sections 18 and 19 will slip down into the flare section of the stem 20 of the lamp, and the bottom surface of the lower baffle plate will be flush with the seal formed when the mount was sealed into the glass envelope of the lamp. The ports 21 of the burners are so poised that the flame 22 will shoot in a downward direction, striking the exhaust tubing near the apex of the conical burner shield sections 18 and 19. By tipping the lamp off down inside in this manner, the possibility of an exhaust tube being tipped off at a point higher than the rim of the seal is thereby eliminated.

Due to slight variances that might be present in the length of different pieces of exhaust tubing or in the length of that portion of the tubing projected into the exhaust rubber 23 by the operator, both of which variances would tend to vary the distance between the point on the tubing at which the torch originally centered itself and the top of the seal, the burner elevation adjusting stud 24, and the burner elevation adjusting bolt 54 are employed as stops to provide for these variances. The reason for an adjustment

of this type is to make sure that, at all times, the cone-like shield sections are flush with the flare and the lower surface of the lower baffle plate is flush with the seal thereby insuring a tipping off of the exhaust tubing below the height of the seal. Since the length of the normal drop taken by the torch after it has centered itself with the exhaust tubing is always the same, the burner elevation adjusting stud 24 and bolt 54 provide the variance "H" for the torch to either dip down by its own weight further than the ordinary length of this drop or to slacken up on this drop once the bottom surface of the lower baffle plate has dropped flush with the lamp seal.

The torch remains in this position down inside the flare long enough for the flame to start melting in the glass tubing. The torch, in a downward motion then pushes the lamp down, away from the upper extremity of the exhaust tubing 20 a distance sufficient to accomplish the severance of the tubing. When the lamp and the torch reach this position of complete severance from the exhaust tubing, the torch moves in an upward direction to a position about $\frac{1}{4}$ of an inch 25 above the tipping seal, where it remains for a short period in order to properly anneal the tip. This annealing feature helps eliminate any strains that might be set up in the tip as a result of the tipping process. When the annealing has been completed, the torch moves in a backward and upward direction back to its normal first position, the machine indexes, and the next head, with a lamp suspended therefrom, moves into a position directly behind the torch and is ready 35 to be tipped off.

The collar 25 projecting from the lower extension of the torch and attached thereto, moves in with the torch when the torch centers itself with the lamp, and in conjunction with the spring 26, 40 acts as a steady rest to help stabilize the lamp in its proper position. The jaw chuck 27, clamps on to the lamp at about its mid-point and along with the clamp on the port 23 into which the exhaust tubing is projected when the lamp is 45 first placed on the machine, acts as the means of holding the lamp in its proper position as it indexes through the different steps in the exhausting process. This chuck is fixed to a frame extending down from the port or head into which the exhaust tubing of the lamp is projected. The grip exerted by the chuck 27 on the lamp is sufficient to hold the lamp after the severing of the exhaust tube. However, the grip is such that it will permit the lamp to slide down through the 50 chuck a short distance when the torch exerts a downward force on the top of the lamp when the exhausting tubing is being severed from the lamp.

The activation of the tipping torch is provided by the action of the cams 34 and 35. These cams are connected to the cam shaft 36 which is supported by the cam frame 37. The motion of the cams 34 and 35 is transmitted through the cam rollers 38 and 39 to the rear lever operating rod 40 and the operating shaft 41, respectively. The drive support 42 is attached to the frame 37. The cams 34 and 35 are shaped in a manner substantially the same as illustrated in the drawings thus providing the activating force necessary to cause the torch to move in the manner described above.

The slide 45, on which the whole torch is mounted, moves in to center itself with the exhaust tubing when the rear lever operating rod 40 moves in a downward direction thus causing the rear lever 43 to pull in a downward direction

since these two are joined by the rear link 44. The slide roller 46 is attached to the slide 45 through the pin 47 and by its action in the elongated slot 48 helps transmit the vertical motion of the rear lever operating rod 40 into the horizontal motion of the slide 45 on which the torch is mounted. When the torch has centered itself with the lamp and the exhaust tubing has been encircled in the tipping cone 8, the slide roller 46 is located at the upper end of the elongated slot. It is then perpendicular to the torch and parallel to the rear lever operating rod 40 and the operating shaft 41. Thus the torch may be moved in a downward direction without having it move forward any further.

After the torch centers itself with the lamp, the operating shaft 41 drops and thus the torch drops down flush with the lamp and remains there until the tubing starts to melt in and thus the torch to which it is connected drops still further, and when it does the lamp becomes completely severed from the exhaust tubing. The shaft then moves up slightly in order to bring the torch up above the tipping seal for annealing purposes. Finally, the operating shaft 41 and the rear lever operating rod 40 both move in an upward direction the latter moving upward at a greater rate of speed than the former in order to accomplish the rearward as well as upward motion drawing the torch back to its original first position. The spring 49, joining the rear lever 43 and the rear lever holder 50, acts as a means of maintaining the rear lever operating rod and the operating shaft, through the cam rollers attached thereto, in a continuously firm contact with the rotating cams. By reason of its position, the spring 49, exerts an inward and downward tension at all times on the rear lever operating rod and the operating shaft, thus accomplishing the desired firm cam contact. The spring 51 directly behind the stud 12 also serves as an adjusting and checking means for when the stud 12 on the plate 13 strikes the spring, the speed with which the torch is moving in a rearward direction is slackened thereby, thus preventing the torch from moving back too far and thus have its lower extremity strike up against the operating shaft 41 or some other member of the apparatus.

What we claim is:

1. In mechanism for tipping off the exhaust tube of an electric lamp, the combination of: an elongated metal plate; a saddle having elongated horizontal slots; a pin passing through said slots and holding said plate rotatably in said saddle, said pin making a sliding fit in said slot; stops to limit the possible rotation of said metal plate around said pin to a small predetermined amount; a slide on which said saddle is mounted; a stud fixing said saddle rotatably on said slide; means for imparting a reciprocating horizontal stroke to said slide; means for imparting an up-and-down motion to said slide at the forward end of said horizontal stroke; a baffle plate having a channel therein and fixed to the forward end of said elongated metal plate; a pair of cooperating scissors-like baffle plates normally meeting under tension and in alignment with the channel in said first-mentioned baffle plate and under said first-mentioned baffle plate; a pair of burner shields, one of said shields being attached to each of the scissors-like baffle plates and meeting, when the baffle plates meet, to form a cone with a small hole at its apex; and a pair

of burners fixed to said elongated metal plate to direct a flame into said cone.

2. In mechanism for tipping off the exhaust tube of an electric lamp having a re-entrant stem, the combination of: a pair of semi-conical burner shields, each having a central notch; a pair of sealing off burners arranged to direct a flame into said shields; and means for imparting a reciprocating horizontal stroke to said shields and said burners, the length of said stroke in its line of motion being automatically adjustable by the location of said exhaust tube in said line of motion.

3. The combination of claim 2 and: means for imparting an up and down motion to said burners and said shields at the forward end of the horizontal stroke.

4. In mechanism for tipping off with burners the exhaust tube of an electric lamp, the combination of: an elongated metal plate for supporting said burners; a saddle having elongated horizontal slots; a pin passing through said slots and holding said plate in said saddle, said metal plate making a rotatable fit around said pin, and said pin making a sliding fit in said slot; stops to limit the possible rotation of said metal plate around said pin to a small predetermined amount; a slide on which said saddle is mounted; a stud fixing said saddle rotatably on said slide; means for imparting a reciprocating horizontal stroke to said slide; and means for imparting an up-and-down motion to said slide at the forward end of said horizontal stroke.

5. In mechanism for tipping off the exhaust tube of an electric lamp having a re-entrant stem, the combination of: an elongated metal plate; a pair of cooperating scissors-like baffle plates normally meeting under tension and supported by said elongated metal plate; a pair of semi-conical burner shields, each having a central notch, one of said shields being attached to each of the scissors-like baffle plates and meeting, when the baffle plates meet, to form a cone with a small hole at its apex; a pair of sealing off burners arranged to direct a flame into said cone; and means for imparting a reciprocating horizontal stroke to said plate, the length of said stroke in its line of motion being automatically adjustable by the location of said exhaust tube in said line of motion.

6. The combination of claim 5 and: means for imparting an up and down motion to said burners and said shields at the forward end of the horizontal stroke.

7. In mechanism for tipping off the exhaust tube of an electric lamp having a re-entrant stem, the combination of: an elongated metal plate; a baffle plate having a channel therein and fixed to the forward end of said elongated metal plate; a pair of cooperating scissors-like baffle plates normally meeting under tension and in alignment with the channel in said first mentioned baffle plate and under said first mentioned baffle plate; a pair of semi-conical burner shields each having a central notch, one of said shields being attached to each of the scissors-like baffle plates, and meeting, when the baffle plates meet, to form a cone with a small hole at its apex; a pair of sealing off burners arranged to direct a flame into said cone; and means for imparting a reciprocating horizontal stroke to said plate, the length of said stroke in its line of motion being automatically adjustable by the location of said exhaust tube in said line of motion.

8. In mechanism for tipping off the exhaust tube of an electric lamp having a re-entrant stem, the combination of: a pair of semi-conical burner shields each having a central notch; a pair of sealing-off burners arranged to direct a flame into said shields; an elongated metal plate for supporting said burners; a saddle having elongated horizontal slots; a pin passing through

5 said slots and holding said plate in said saddle; a slide on which said saddle is mounted; means for imparting a reciprocating horizontal stroke to said slide; and means for imparting an up-and-down motion to said slide at the forward end of said horizontal stroke.
